UNITED STATES PATENT OFFICE.

DAVID C. BELLIS, OF ELIZABETH, NEW JERSEY, ASSIGNOR TO ROBERT W. SCOTT, OF PHILADELPHIA, PENNSYLVANIA, AND LOUIS NAPOLEON DEVON WILLIAMS, OF ASHBOURNE, PENNSYLVANIA.

KNITTING-MACHINE.

SPECIFICATION forming part of Letters Patent No. 714,998, dated December 2, 1902.

Application filed February 28, 1902. Serial No. 96,095. (No model.)

To all whom it may concern:

Be it known that I, DAVID C. BELLIS, a citizen of the United States, and a resident of Elizabeth, New Jersey, have invented certain 5 Improvements in Knitting-Machines, of which the following is a specification.

The object of my invention is to so construct a knitting-machine as to adapt it for the production of fabric consisting of two 10 webs, one overlying the other, said webs being united at appropriate intervals by yarn of one web engaging with the other web.

In the accompanying drawings, Figure 1 is 15 a sectional view of a knitting-machine constructed in accordance with my invention. Fig. 2 is a sectional view of part of the machine, illustrating the operation of tying the two webs together; and Figs. 3 and 4 are diagrammatic views illustrating the character 20 of the needles and cams employed in the machine.

One of the needle-carriers is represented at 1 in the drawings and the other at 2, these 25 needle-carriers being so disposed that their needles work in planes at a right angle to each other. Each of the needle-carriers has its appropriate cam-carrier, said cam-carriers being indicated at 3 and 4, respectively. The 30 needle-carriers may be stationary and the cam-carriers may be caused to rotate, or the reverse construction may be adopted, the needle-carriers rotating and the cam-carriers being stationary.

One or more yarn-guides are employed for 35 each needle-carrier, these yarn-guides being so disposed that one of them or one set of them will normally feed yarn to the needles of one carrier only, the other guide or set of guides feeding yarn to the needles of the other 40 carrier only. Thus 5 represents a guide for feeding yarn to the needles of the carrier 1, and 6 represents a guide for feeding yarn to the needles of the carrier 2, so that two separate and independent webs will be produced, 45 one upon the needles of one carrier and the other upon the needles of the other carrier. At intervals, however, the webs may be connected together by projecting certain of the needles of one carrier so as to receive yarn 50 from a guide which normally operates in con-

junction only with the needles of the other carrier. Thus, as shown in Fig. 2, a needle of the carrier 2 is projected so as to receive yarn from the guide 5. Hence a loop or stitch of this yarn will be drawn by said needle into the web normally produced by the needles of the carrier 2, and the two webs will thus be connected together, a stitch being formed if the needle of the carrier 2 is projected far enough to cast the stitch already on it and a 60 simple loop being drawn if the needle is not thus projected.

In machines of fine gage, having the needles of one carrier disposed directly in line with the needles of the other carrier, a needle 65 of one carrier will be held in the retracted position when a tying-needle of the other carrier is projected, as shown in Fig. 2; but in machines in which the needles of one carrier play between the needles of the other carrier this 70 will not be necessary, as the needles of both carriers may be projected at the same time.

In Figs. 3 and 4 I have shown an arrangement of needles and cams which may be adopted in carrying out my invention, the 75 cams being shown in each case as developed in a straight flat plane instead of following the curved or circular course which they actually assume in the machine.

All of the needles of the carrier 2 have 80 short butts with the exception of those needles which are to act as tying-needles, the butts of these needles being longer than those of the other needles, and the cam-carrier, which coöperates with the needles of the carrier 2, has cams 9 and 10, the cams 9 acting upon the butts of all of the needles and the cam 10 acting only upon the long butts of the tying-needles. In like manner the carrier 1 has needles, all of which have long butts except the needles which work in line with the tying-needles of the carrier 2, these needles having short butts, and the cam-carrier 3, which operates in conjunction with the needles of the carrier 1, has cams 11 and 12, the 85 cams 11 projecting all of the needles and the cams 12 projecting all except the short-butted needles. The cams 9 and 11 of the two cam-carriers are so disposed that the needles of one carrier will be projected only when those 90 95 100

of the other carrier are retracted, the tying-
needles, however, being projected by the cam
10 at the same time that the needles of the
carrier 1 are being projected by the cam 12,
5 so as to receive yarn from the guide 5 at the
same time that the guide is feeding yarn to
the needles of the carrier 1.

The two webs are not intended to be tied
together in every course, a number of courses
10 of each fabric intervening between those
courses in which the tying is effected. Hence
in the claims I have used the term "alter-
nate courses" to specify this feature of con-
struction of the machine. The tying-needles,
15 therefore, after once being projected so as to
receive yarn from the other fabric will have
to be prevented from again receiving such
yarn until a number of intervening courses
of fabric have been knitted, and when the
20 machine has but a single yarn-guide for each
set of needles this may be accomplished by
projecting the tying-needles to receive the op-
posite yarn only once in so many rotations of
the machine by the use of any ordinary form
25 of adjustable projecting-cam, or in the case
of a machine using a number of guides the
cam which projects the tying-needle may
form one of a number of cams which act upon
said needles, the other cams only projecting
30 the needles so as to receive the yarn from
their own guides, as in the construction
shown in Figs. 3 and 4, in which the cams 10
and 12 are those which act upon the needles
at the tying-point, the cams 9 and 11 form-
35 ing part of a series which project the needles
so as to receive yarn from their own guides
at different knitting-points.

While I have shown my invention as applied
to a machine of the ordinary rib type having
40 a cylinder and dial, it will be evident that
it can be applied with equal facility to any
machine having two needle-carriers disposed
at opposing angles, and my invention is,
moreover, not limited to cylindrical machines
45 for producing tubular web, but is applicable
as well to machines having straight needle-
beds for producing flat web, and although I
have shown the invention as applied to a ma-
chine using latch-needles it will be evident
50 that it can be embodied also in machines em-
ploying in either or both carriers needles with
spring-beards.

Having thus described my invention, I

claim and desire to secure by Letters Pat-
ent—

55

1. A knitting-machine in which are com-
bined two sets of needles, carriers therefor,
one or more guides operating to feed yarn to
each set of needles, and means whereby cer-
tain of the needles of one set may at inter-
vals in alternate courses be caused to engage
60 with the yarn normally fed to the needles of
the other set, substantially as specified.

2. The combination in a knitting-machine,
of a pair of needle-carriers each having a cir-
70 cular series of needles, one or more yarn-
guides operating in conjunction with the nee-
dles of each carrier, and means for causing
certain of the needles of one carrier to engage
at intervals in alternate courses with the knit-
75 ing-yarn normally fed to the needles of the
other carrier, substantially as specified.

3. The combination in a knitting-machine,
of a pair of needle-carriers each having nee-
dles, some of the needles of one carrier being
80 differentiated from the others, one or more
yarn-guides for each set of needles, cams for
operating the needles of each carrier so as to
cause them to receive yarn from its corre-
sponding guide or guides, and cams for op-
85 erating the differentiated needles so as to
cause them to receive in alternate courses
yarn from a guide which is normally oper-
ative in connection only with the needles of
the other carrier, substantially as specified.

4. The combination in a knitting-machine,
of two needle-carriers each having needles
some of which are differentiated from the
others; a yarn guide or guides operating in
90 conjunction with the needles of each carrier,
and cams whereby the needles of each car-
rier may be projected so as to receive yarn
from its corresponding guide or guides, and
whereby certain needles of one carrier may be
95 projected to receive in alternate courses yarn
from a guide of the other needle-carrier, and
the corresponding needles of said other car-
rier may be held in the retracted position, sub-
stantially as specified.

In testimony whereof I have signed my 100
name to this specification in the presence of
two subscribing witnesses.

DAVID C. BELLIS.
